2,094,677

SCREEN APPARATUS FOR TELEVISION RECEIVERS

Kurt Schlesinger, Berlin, Germany

Application March 23, 1936, Serial No. 70,425
In Germany March 29, 1935

3 Claims. (Cl. 250—36)

The invention relates to scanning apparatus supplying deflection voltages to the deflection systems of television tubes.

It has been found that with scanning apparatus for television receivers producing linear movement of the image point which make use of amplifying tubes for amplifying the saw-tooth voltages, interfering distortions result in the image owing to the curved characteristic of the amplifying tubes.

In the drawing Fig. 1 shows a circuit diagram of a scanning apparatus constructed according to the invention.

Fig. 2 shows a saw-tooth voltage curve plotted with respect to the time.

In Fig. 1 there is shown a typical relaxation-oscillation connection system, in which a condenser 2 is charged through the medium of a very large resistance 3 by an anode battery 4.

An amplifying tube 5 is coupled by way of a condenser 6 with the condenser circuit 1, 2, 3, and the amplified potential is taken from its anode resistance 7 and conducted to the deflecting plate 8 of the Braun tube 9.

It is known that by wasting potential, i. e., by adjusting the circuit so that very small oscillation amplitudes at the condenser 2, and using a d. c. potential source 4 which is fifty to one hundred times greater than the maximum potential reached by the condenser the potential curve reaching the grid of the amplifying valve 5 may be rendered strictly linear. The deflecting potentials applied to the Braun tube 9, however, are nevertheless not linear with respect to time.

Fig. 2 shows the nature of the curve of this latter oscillation. The curve of the voltage applied to the grid of valve 5 is represented by 10 and has a strictly linear ascent. The voltage capable of being utilized at the Braun tube 9 is always as represented by the curve 11. This distortion is not to be explained by incorrect adjustment of the grid bias of 5, but still remains even if the valve 5 has been carefully adjusted to operate on the linear range of its characteristic.

It is accordingly assumed that the explanation for the error is to be found in a curvature in the characteristic occurring in general in the case of electronic tubes. The error itself is merely of the order of a small percentage, i. e., is very small. According to Langmuir's law of emission, the steepness of a characteristic must increase with the anode current. As a matter of fact there is an error of this kind in the case of all relaxation apparatus which have been tested by the applicant.

According to the invention, a remedy is provided by the fact that at some point between the relaxation-oscillation generator 1, 2, 3 and the consuming apparatus 8, 9 there is provided a circuit element, which transmits the high frequencies of the relaxation curve in preference to the basic frequency thereof. In other words, there is connected between relaxation oscillation generator and consuming apparatus, and preferably, therefore, in front of the grid circuit of the subsequent amplifier 5, a coupling member which already discloses a declining degree of transmission in the case of the basic frequency of the relation oscillation—a so-called high-pass.

In Fig. 1 the high-pass according to the invention is designated 10, 11. The basic frequency of the relaxation oscillation is no longer able to traverse the condenser 10. It accordingly suffers at the resistance 11 a loss of potential which is designated by the potential divider 11—12.

The higher frequencies of the saw-tooth curve traverse the condenser 10 and accordingly arrive at the grid of 5 without dissipation, i. e., in preference. In certain cases the resistance 11 may also be omitted. In the following there are quoted by way of example indications in respect of the numerical dimension.

1. Image change apparatus:

Basic frequency	25 periods	30
Higher harmonics up to	100th harmonic	
Condenser	10:01 mf.	
Resistance	12:10 ⁶ ohms	

2. Line relaxation apparatus:

Number of lines	180 per image	35
Basic frequency of lines	4500 periods	
Harmonics up to approx	400,000 periods	
Condenser	10:0.003 mf.	
Resistance	11:10,000 ohms	
Resistance	12:0.1 megohm	40

The basic frequency in the case of this high pass is weakened in a ratio of

$$\frac{10^4}{10^5}$$

45

i. e., by 10%, and the high frequency is transmitted without loss. It is possible with high-pass couplings of this kind, which according to the invention may also be introduced into later circuits, for example before the Braun tube, to perform a compensation of the natural curvature of the characteristic of the tube.

The same effect as obtained by the condenser 10 and the resistance 11 may also be obtained in certain cases, viz., in the case of low-ohmic

55

grid resistances 12, by a series choke 13. The member 10, 11 is then omitted.

I claim:

1. A scanning apparatus for television receivers comprising a relaxation oscillation generator, said generator producing voltages of saw-tooth wave form having higher frequency and lower frequency components, an amplifier and coupling means comprising means for passing said higher frequency components better than said lower frequency components for coupling said amplifier with said relaxation oscillation generator.
2. A scanning apparatus for television receivers comprising a relaxation oscillation generator, said generator producing voltages of saw-tooth wave form having higher frequency and lower frequency components, an amplifier and coupling means comprising means for passing said higher

frequency components better than said lower frequency components for coupling said amplifier with said relaxation oscillation generator, said means consisting of a condenser and a resistance connected in parallel.

3. A scanning apparatus for television receivers comprising a relaxation oscillation generator, said generator producing voltages of saw-tooth wave form having higher frequency and lower frequency components, an amplifier and coupling means comprising means for passing said higher frequency components better than said lower frequency components for coupling said amplifier with said relaxation oscillation generator, said means consisting of a resistance and a choke connected in series.
